Loris Nahemow

UNITED STATES PATENT OFFICE.

SAM MOSKOWITZ, OF BROOKLYN, NEW YORK.

DESIGN FOR A BUFFET.

53,457.

Specification for Design.

Patented June 17, 1919.

Application filed March 27, 1919. Serial No. 285,684. Term of patent 3½ years.

To all whom it may concern:

Be it known that I, SAM MOSKOWITZ, a citizen of Russia, and resident of the borough of Brooklyn, in the county of Kings and State of New York, have invented a certain new, original, and ornamental Design for Buffets, of which the following is a specification, reference being had to the accompanying drawing, forming part thereof.

The figure is a perspective view of a buffet, showing my new design.

I claim:

The ornamental design for a buffet as shown.

Signed at New York city in the county of New York, and State of New York, this 18th day of March, 1919.

SAM MOSKOWITZ.
